Primary Examiner — Cynthia Ramirez*Assistant Examiner* — Llorelly Martinez-Rivera(74) *Attorney, Agent, or Firm* — Tai W. Nahm; Miller Thomson LLP.**CLAIM**

The ornamental design for a trim reveal extrusion, as shown and described.

DESCRIPTION

FIG. 1 is a perspective view of a trim reveal extrusion showing my new design.

FIG. 2 is a cross-sectional view thereof; and,

FIG. 3 is an end elevational view thereof illustrating an exemplary environmental use.

The broken lines are for environmental purposes only and form no part of the claimed design.

The trim reveal extrusion is shown with a symbolic break in its length. The appearance of any portion of the trim reveal extrusion between the jagged break lines form no part of the claimed design.
